UNITED STATES PATENT OFFICE

2,597,051

TEMPORARY BUTTON FASTENER

John Auér, East Norwalk, Conn.

Application July 6, 1944, Serial No. 543,654

4 Claims. (Cl. 24—103)

1

This invention relates to a temporary button fastener and has for an object to provide an improved simple means for temporarily securing buttons to garments during fitting of the garment, such for example as a lady's or gentleman's suit coat or lady's dress during fitting, so that the buttons could be properly located and easily shifted to secure the best location before permanently fastening them to the garment.

Another object is to provide an improved fastener or holder which will secure the buttons temporarily and quickly so that they may be easily and quickly adjusted or shifted to different desired locations to observe their effect and determine their proper location during fitting of a garment, but one which will hold them sufficiently securely that they will not fall off or become displaced during the fitting.

A further important object is to provide a fastener of this character which may be applied to and removed from the fabric or garment wholly from the right or outside and without turning the fabric or requiring any operation on the inner or wrong side.

With the foregoing and other objects in view I have devised the constructions illustrated in the accompanying drawing forming a part of this specification. It is, however, to be understood the device is not limited to the specific construction and arrangement shown but may embody various changes and modifications within the scope of the invention.

In these drawings:

Fig. 1 is a front elevation of a portion of a garment showing a button secured thereon by my improved temporary fastener;

Fig. 2 is a vertical section substantially on the line 2—2 of Fig. 1;

Fig. 3 is a side elevation of a somewhat modified form of fastener;

Fig. 3a is a top plan view thereof;

Figs. 4, 5 and 6 are side elevations of different modified construction;

Figs. 7 and 8 are vertical sections through buttons on other modified forms of fastener, the fastener being shown in side elevation;

Fig. 9 is a side elevation of another somewhat modified construction;

Fig. 9a is a top plan view thereof; and

Fig. 10 is a side elevation of still another modified form.

Referring first to Figs. 1 and 2, a portion of a piece of garment or fabric is shown at 11 upon which is fastened and supported a button 12 by one form of my improved fastener. This fas-

tener comprises a wire 13 pointed at one end, in this case the upper end 14, and bent backwardly and downwardly upon itself to form a hooked portion 15. At an intermediate portion 5 it is bent laterally and folded upon itself to form a loop 16 adapted to pass through one of the thread openings 17 of the button to retain the button on the fastener. The portions of the wire forming the intermediate portion of this loop are 10 curved outwardly as shown at 18 so that the loop is wider at the intermediate portion than it is at its opposite ends 19 and 20. The wire being resilient it thus forms a spring or resilient loop, and the width of the loop at its widest portion 15 is greater than the diameter of the thread opening 17 of the button so that as the loop is forced through the opening in the button it is compressed and then expands somewhat to retain the button on the fastener. In use, to secure 20 the button on the garment all that is necessary is to insert the upper or hooked end portion in the garment at the desired location and it will be held during the fitting without permanently fastening the button to the garment. The proper 25 location can be then marked on the garment and the button and the temporary fastener easily removed without in any way marring the garment, and to permit permanent fastening of the button. It can be applied and removed wholly from the 30 front without requiring turning or any operations on the wrong side of the garment. At the outer end portion of the loop, as indicated at 19, the opposite sides are closely folded together to make a short guiding end portion for easy insertion 35 in the thread opening in the button, to guide the loop into this opening and facilitate placing the button on the fastener. The downward extension 13b below the loop rests against the front of the fabric back of the button and helps to hold 40 the button straight.

In the form shown in Figs. 3 and 3a the free end portions of both sides of the forwardly extending loop extend upwardly as shown at 21 and are then bent backwardly and downwardly at 22 and are pointed as shown at 23 to hook into the garment. The loop is in the horizontal plane instead of the vertical as in Figs. 1 and 2, and as these hooked portions are laterally spaced they form a more stable lateral support for the button than does the form of Figs. 1 and 2. The form of the loop 16, however, is the same and is inserted through the thread opening in the button which secures it in the same way as does the first form.

55 In the form shown in Fig. 4 the fastener is

very similar to that of Figs. 1 and 2, except that the downwardly extending portion 24 below the loop 16 instead of being straight so as to lie on the face of the fabric as does the extension 13b of Figs. 1 and 2, is offset or bent backwardly 5 as indicated at 25, and then downwardly and is pointed as shown at 26. The two points 14 and 26 therefore extend in the same direction or downwardly in substantial alignment. The upper hook portion 15 operates the same as in Figs. 10 1 and 2 but the lower pointed end 26 being also at the same time inserted into the fabric below the loop 16 for mounting the button prevents the lower end swinging outwardly or laterally and makes a more stable support for the button.

In the form of Fig. 5 the structure is substantially the same as that of Figs. 1 and 2 except that the portion 27 above the loop and the extension 28 below the loop are made somewhat shorter and would be hidden behind the button.

In the form shown in Fig. 6 instead of the upper end being bent backwardly and downwardly it is offset backwardly slightly as at 29 with the point 30 extending upwardly therefrom. This offset forms a sort of shoulder 31 so that when the upper pointed portion is inserted in the fabric this shoulder will prevent its sliding downwardly and release it. The lower end portion of the downwardly extending part 32 is inclined outwardly as shown at 33 and forms a small hook 34 to engage the fabric and retain the device in position and help retain the upper pointed end in the fabric.

In Fig. 7 the fastener is formed with an intermediate looped portion 35, but instead of being a substantially closed loop as in the previous figures it is formed by bending the wire forwardly and downwardly leaving the lower portion 36 substantially straight and pointed as shown at 37. The upper end portion 38 extends upwardly from the forward end of the loop and may be provided with a head 39 at its upper end. This looped portion passes through the thread opening 17 in the button, but is inserted in the button by passing the lower pointed portion 37 backwardly through the opening first, so that the button lies on the forward part of the loop adjacent the upright forward portion 38. When the lower portion 36 is inserted in the fabric the button is held closely adjacent the surface of the fabric and retained on the loop by the upright forward portion 38.

The form of Fig. 8 is similar to that of Fig. 7 except that instead of bending the forward portion of loop 35 sharply in the plane of the loop as it is joined to the upright portion 38 as in Fig. 7 it is looped backwardly and upwardly on itself as shown at 40. Otherwise it is the same as that of Fig. 7 and is used in the same manner.

The form of device shown in Figs. 9 and 9a is similar to that of Fig. 3 with the loop 16 arranged in the horizontal plane. The extension of one side of this loop extends outwardly at 21 and is bent backwardly and downwardly at 22 the same as in Fig. 3, but the extension 41 at the other side of the loop is merely formed with a small hook 42 to engage into the fabric after the larger hooked portion 22, 23 is hooked into the fabric. This little hook 42 acts to retain the larger one in the fabric and also to hold the fastener and the button in the upright position on the face of the fabric.

The form shown in Fig. 10 is similar to that of Figs. 9 and 9a except that the loop 16 is in the vertical plane instead of the horizontal. The

lower portion 43 of the loop is bent upwardly at 44 and then backwardly and downwardly to form the hook 22. The extension 45 of the upper portion of the loop is provided with a small hook 46 similar to the hook 42 of Fig. 9 to engage in the fabric and hold the larger hook 22 in the fabric to prevent its being accidentally separated during the fitting operation.

In each of the forms of Figs. 1 to 6 and 9 and 10 the loop 16 is preferably somewhat larger than the diameter of the thread opening 17 of the button when there is no button on the fastener, so that when the loop is inserted through this thread opening it will be compressed and then expand somewhat so as to retain the button on the fastener by its expansive action. As shown in Fig. 2 the loop is compressed somewhat while in the other figures it is shown as expanded somewhat.

It will be understood from the above that each of the forms shown provides a simple and effective means for temporarily fastening buttons to garments, such for example as a man's or lady's coat or ladies' dresses, while they are being tried on or fitted, as for example while the tailor is fitting the coat or suit, so that he may place the buttons at different locations to observe the effect and place them in any location desired to get the best and proper effect without permanently fastening the buttons to the garment. However, they hold the buttons sufficiently secure so that they will not fall off or become displaced during the fitting operation. After the proper location, however, has been determined the place can be readily marked, then the temporary fastener removed to permit permanent fastening of the button to the garment, or these temporary fasteners can be left in the garment to hold the buttons in the proper locations until it is desired to permanently fasten the buttons. In short, this fastener provides a simple and effective means for easily, quickly and temporarily securing the buttons to the garment during the fitting so that they can be properly located and easily and quickly shifted to different locations to determine the best and most desirable effect or appearance before permanently fastening the buttons.

An important advantage of this fastener is that it may be applied and removed to and from the fabric wholly from the outside and without turning the fabric or requiring any operation on the inner or wrong side.

Having thus set forth the nature of my invention what I claim is:

1. A temporary button fastener comprising a wire pointed at both ends with one end portion having a backward bend to point in the same direction as the other end so that both ends may be inserted in fabric with a single movement, and an intermediate portion being formed into a loop extending laterally and adapted to be inserted through a single thread opening in a button, said loop being resilient and wider than the opening to retain the button on the fastener, and the portions of the wire immediately adjacent the loop being in substantial alignment and extending in opposite directions from the loop.

2. A temporary button fastener comprising a wire pointed at one end and having a backward bend upon itself to form a hooked portion, and said wire at the base of the hook extending laterally outwardly and forming a loop adapted to be inserted through a single thread opening in a button, the opposite sides of said loop being laterally spaced and outwardly curved in opposite

directions and also resilient and wider than the opening to retain the button on the fastener, and the sides of the closed end of the loop forming a fold with the sides closely together forming a short guiding end portion for easy insertion in the thread opening in the button.

3. A temporary fastener for a substantially flat button provided with thread openings through it, comprising a pointed wire adapted to pierce a fabric, said wire having a yieldable loop at an intermediate portion adapted to pass through a single thread opening only to retain the button on the wire and at the surface of the fabric in which the point is inserted, the intermediate portion of the loop being normally wider than the button opening and the outer end portion of the loop comprising a fold with the opposite sides closely together forming a short guiding end portion for easy insertion of the loop in the thread opening, said fastener being readily removable from the button by withdrawing the wire from the opening to permit sewing of the button on the fabric.

4. A temporary button fastener comprising a wire pointed for insertion in a fabric to secure it thereto and having a bend upon itself intermediate its length to form a loop adapted to be passed through a single thread opening in a button, said loop being resilient and wider at an intermediate portion than at the ends of the loop

and also normally wider than said opening so that it is compressed as it passes through the opening and then expands so as to retain the button on the fastener and at the surface of the fabric in which the point is inserted, and the outer end portion of the loop comprising a fold with the opposite sides closely together and narrower than the opening to form a short guiding end portion for easy insertion of the loop in the thread opening.
